UNITED STATES PATENT OFFICE.

JOSEPH E. BURGESS, OF ST. LOUIS, MISSOURI, ASSIGNOR TO UNITED RAILWAYS COMPANY OF ST. LOUIS, OF ST. LOUIS, MISSOURI, A CORPORATION OF MISSOURI.

WIRE-CONNECTOR.

1,216,545.

Specification of Letters Patent. Patented Feb. 20, 1917.

Application filed April 21, 1916. Serial No. 92,618.

To all whom it may concern:

Be it known that I, JOSEPH E. BURGESS, a citizen of the United States, residing at the city of St. Louis and State of Missouri, have 5 invented a new and useful Wire-Connector, of which the following is a specification.

This invention relates to wire connectors, and it has particular reference to devices adapted for use to connect electric line wires 10 whether used for electric railways or other purposes.

An object of the invention is to provide a device adapted to be connected to the adjacent portions of a broken wire of an electric 15 circuit to serve as a temporary connection between the portions of the broken wire so that the circuit will not be interrupted during the time that the broken wire is being permanently repaired.

20 An additional object of the invention is to provide a device of the character mentioned adapted to be employed in connection with the wire stretching mechanism and to serve as a temporary removable connection and as 25 a part of the electric circuit during the time that the wires are being repaired.

Other objects will appear from the following detailed description of the invention in which reference is made to the accompanying drawings, wherein—

Figure 1 is a view of the device in connection with the adjacent portions of a broken electric wire.

Fig. 2 is a detailed sectional view illustrating one of the brackets and also illustrating the telescoping connecting members.

Fig. 3 is an enlarged sectional view on the line 3—3 of Fig. 2.

Fig. 4 is a similar sectional view on the line 4—4 of Fig. 2.

Fig. 5 is a sectional view on the line 5—5 of Fig. 1.

The adjacent portions of a broken electric line wire are indicated by 1 and said portions are shown in connection with the usual wire stretching mechanism comprising the clamps and pulley devices 2 and the ropes 3. The adjacent ends of the broken wire are stretched and drawn together by this wire stretching mechanism, so that the wire may be repaired and the broken ends permanently connected. It is obvious that without the provision of some device to serve as a connection between the ends of the broken wire

the electric circuit will remain broken or 55 interrupted so long as the ends of the wire 1 are disconnected.

The present invention comprises a device adapted to be used as a temporary removable connection between the adjacent portions of the broken wire and is particularly 60 adapted for use in connection with trolley wires, so that the trolley wheel may operate against the device, thus preventing the car from stopping as otherwise might occur. 65

In the embodiment illustrated there are two connecting brackets of duplicate construction, each comprising a base portion 4 and two approximately parallel flanges 5, separated to form a space for receiving 70 wires. The base portions 4 preferably taper toward their outer extremities so that their lower surfaces are normally continuous with the lower surfaces of the wires and thus constitute no material obstruction to the operation of the trolley wheel. The flanges 5 are provided with holes 6 adapted to receive the removable members 7 so as to bind the brackets in connection with the wires which are seated upon the base portions 4 between the flanges 5 and also between the base portions 4 and the members 7. 75

One of the brackets is attached to a tubular connecting member 8 and the other bracket is connected to a similar connecting 85 member 9 which is movably extended into the member 8. By this construction the connector comprising the two brackets and the connecting members 8 and 9 may be extended to considerable length approximately twice 90 the length of either of the connecting members, or the connector may be reduced to approximately the length of one of said members or to any length intermediate of the two extremes. This provides a conveniently 95 adjustable connector which may be adjusted to bridge any space usually encountered in broken wires so that the trolley wheel may operate continuously against the wire and the connector and the car be driven under 100 power while passing the break in the wires.

The tubular connecting member 8 is provided with two diverging arms 10 between which the rope 3 of the wire stretching mechanism is received. The arms are provided with a number of holes 11 which receive the removable elements 12 passing above the rope so that the intermediate 105

portion of the connector and the stretching mechanism are connected, thus reinforcing and strengthening both.

A connector of this construction constitutes a convenient and efficient equipment for effecting temporary connection between the adjacent portions of broken trolley wires and the like, and by use of which interruption of traffic after the device is applied is avoided. This is of especial importance in communities in which the cars using the line of the broken wire are numerous, inasmuch as very little time is required to apply the temporary connector which may be retained in position until the proper opportunity is afforded to make permanent repair, as when the traffic has become reduced. The device also enables the car to travel past the break in the wire under power and thus avoids delays incident to the frequent stops of cars in passing the point of the break.

I am aware that there may be various alterations and modifications in the construction and arrangement of the different parts without departing from the scope of the invention. Therefore, I do not restrict myself to identical features of construction or arrangement, but contemplate variations within the scope of mechanical equivalents so that the device may be made in any preferred form in which it will most efficiently subserve the functions required of it.

What I claim and desire to secure by Letters Patent, is:

1. A device of the character described comprising brackets, means for removably connecting the brackets to the wire, a connector between the brackets adapted to place the two parts of the broken wire in circuit with each other, and an element for supporting the device in connection with the adjacent separate wire stretching mechanism.

2. A device of the character described comprising two brackets, means for removably connecting the brackets to adjacent portions of the broken wire, a connector between the brackets comprising two relatively long telescoping parts in connection with said brackets respectively, adapted to place the two parts of the broken wire in circuit with each other, two diverging arms in connection with one of said parts adapted to receive the adjacent wire stretching mechanism between them, and an element for holding the wire stretching mechanism between said arms.

3. A device of the character described comprising two brackets of duplicate construction each composed of a base having its upper surface inclined downwardly and outwardly, whereby the under surfaces of the brackets are normally in alinement with the under surfaces of the wires resting there-

on, and flanges rising from the base and adapted to receive the wire between them; means for securing the flanges to the wire, and a connector between said brackets comprising two relatively long telescoping parts connected to said brackets respectively, adapted to place the two parts of the broken wire in circuit with each other.

4. A device of the character described comprising two brackets, releasable devices for supporting the brackets in connection with adjacent portions of a broken wire, an expansible connection between said brackets adapted to serve as an electric conductor between the adjacent portions of the wire, and an element for supporting the device in connection with adjacent separate wire stretching mechanism.

5. A device of the character described comprising two brackets, releasable means for supporting the brackets in connection with adjacent portions of a broken wire, an expansible connection between said brackets adapted to serve as an electric conductor between the adjacent portions of the broken wire and to transmit power for driving a car, and means for supporting the device in connection with adjacent wire stretching mechanism.

6. A device of the character described, comprising two brackets of duplicate construction each composed of a base having its upper surface inclined downwardly and outwardly, whereby the under surfaces of the brackets are normally in alinement with the under surfaces of the wires or resting thereon, and flanges rising from the base and adapted to receive the wire between them; means for securing the brackets to the wire; a connector between said brackets comprising two relatively long telescoping parts connected to said brackets respectively adapted to place the two parts of the broken wire in circuit with each other; and a supporting element in connection with one of said parts for supporting the device in connection with adjacent separate wire stretching mechanism.

7. A device of the character described, comprising two brackets of duplicate construction each composed of a base having a seat for the wire therein inclined downwardly and outwardly, whereby the under surfaces of the brackets are normally in alinement with the under surfaces of the wires in connection therewith; means for securing the brackets in connection with the stretched wire at opposite sides of adjacent separate wire stretching mechanism; and a connector between said brackets of greater length than the adjacent separate wire stretching mechanism comprising two relatively long telescoping parts connected to said brackets respectively and adapted to place the two parts of the broken wire in

circuit with each other from opposite sides of the wire stretching mechanism.

8. A device of the character described, comprising two brackets of duplicate construction each composed of a base having a seat for the wire therein inclined downwardly and outwardly, whereby the under surfaces of the brackets are normally in alinement with the under surfaces of the wires in connection therewith; means for securing the brackets in connection with the stretched wire at opposite sides of adjacent separate wire stretching mechanism; a connector between said brackets of greater length than the adjacent separate wire stretching mechanism comprising two relatively long tele-

scoping parts connected to said brackets respectively and adapted to place the two parts of the broken wire in circuit with each other from opposite sides of the wire stretching mechanism; and a supporting element in connection with one of said telescoping parts for supporting the intermediate portion of said device in connection with the wire stretching mechanism. 20

In witness whereof, I have signed this specification in the presence of two subscribing witnesses.

JOSEPH E. BURGESS.
